PAINTBRUSH

Lawrence S. Hewes, Gravenhurst, Ontario, Canada, assignor, by mesne assignments, to Rubberset Company, Newark, N. J., a corporation of New Jersey

Application June 28, 1938, Serial No. 216,203

4 Claims. (Cl. 15—192)

This invention relates to improvements in the construction of brushes and to certain means and methods involved in the production of the brushes.

Although, in its broader aspects, the invention relates to brushes in general, it particularly pertains to brushes of the type composed of an assembled body of bristles and intended for use in painting or coating surfaces with materials of a more or less fluid character. More particularly the invention, in certain of its aspects, relates to that type of brush commonly known as a "chisel end" brush. Such a brush, as its name implies, has the free, operative end of the bristle body tapered inwardly from each face to provide either a rounded, convex edge or a flat, blunt edge of reduced width.

An object of the invention has been to provide a construction in which a maximum length of the projecting, active portion of the bristles may be obtained with a minimum and substantially uniform length of the individual bristles, without impairing the strength of the brush or decreasing its serviceability but in fact improving these qualities.

In one embodiment of the invention there is provided a plurality of layers of bristles, the length of the layers differing relatively but each layer being composed of bristles of substantially the same predetermined length, and the layers being so arranged, relatively, as to form at the upper or non-operative end of the assembled body of bristle-layers one or more depressions.

An advantage resulting from certain applications of the invention is that it permits the retention of a substantial portion of the natural, relatively soft or flag ends of the bristles in forming the shaped operative end of the brush and with a minimum of trimming.

Other objects and advantages of the invention will become apparent from the detailed description of various embodiments of the same which will now be given in conjunction with the drawings wherein certain preferred and illustrative forms have been disclosed as typifying the invention. In the accompanying drawings which constitute a part hereof, together with the specifications,

Fig. 1 is a side elevation of the head of a paint brush embodying the invention.

Fig. 2 is an end elevation of the brush shown in Fig. 1.

Fig. 3 is a vertical section on an enlarged scale, taken on the line 3—3 of Fig. 1, taken in the direction of the arrows.

Fig. 4 is a view similar to Fig. 3 but illustrating a modified shape of the free end of the bristles.

Fig. 5 illustrates on an enlarged scale a step in the construction of the brush.

Fig. 6 shows a further step in the construction of the brush, and

Figs. 7, 8, 9, and 10, illustrate the same stage of construction as Figure 6 with respect to modified forms of brushes embodying the invention.

In Figs. 1, 2 and 3 is shown a brush which, in general, comprises a body of bristles 1 fixedly mounted in a ferrule 2, to which latter is also attached a handle 3. The free or effective end 4 of the bristle body 1 may have various contours, but for the purpose of the illustrative examples of the invention, said end is shown either with a more or less convex or rounded cross section as seen at 4 in Figs. 2 and 3 or with an angular cross section as seen at 5 in Fig. 4. In either case the sides of the bristle-body taper inwardly adjacent their free ends toward a narrow edge extending across the width of the brush.

Bristles, as commonly used in brushes of the class hereinbefore referred to, have a heavy or butt end and a soft, light or flag portion. It is desirable to leave the light or flag portion free for the effective or active end of a brush, so that, preferably, the bristles of a bunch are therefore bundled with like ends together in the construction of a brush. As illustrated in Fig. 3 the mass of bristles 1, whose individual units are preferably of approximately equal lengths, may be so bunched by any suitable device or means, such as a mould, that the upper end of the mass conforms to the shape of and substantially fills the lower portion of ferrule 2; the grouped end 6 of the bristle butts is preferably so positioned as to present a valley 7, the outline of which substantially corresponds to the contour of the free or flag ends of the bristles at 4 (Figure 3) or at 5 in the modified form of Fig. 4. Either of the ends of the bristle-body may be used to shape the active ends of the bristles; to produce the desired shape the contacting contour of the mould when one end is used in the shaping operation would be the reverse of that required when the other end is used for this operation. This bunching of the bristles may be accomplished, for example, by loosely encasing a substantial length of the bristle-body with a mould adapted to completely embrace one of the ends of the bristles and so shaped opposite the ends of the bristles as to give the desired predetermined contour thereto, the mould, at the same time, being adapted to retain the bristles in assembled condition in the bristle-body. By imparting a vibratory motion to this mould the ends of the bristles assume substantially the shape of the closed end of the mould and the bristle body is desirably formed. Wing-like projections 8, 8, rise at the sides of the valley 7 and are utilized in a manner to be hereinafter disclosed. If it is desired, these wing portions may be somewhat more extended, than illustrated, by forming the outer layers of the bristle-body on each side of bristles of a length somewhat in excess of those forming the main body of the mass.

In Fig. 5 the ferrule 2 is shown placed in an intermediate position on the formed body of bristles 1, this being a step in the fabrication of the brush enabling the butt ends of the bristles to be treated with a binding compound, preferably one having a rubber base, in any suitable manner, such as by dipping. The binder is in this way permitted to fill the spaces between the butts to a predetermined distance and serves to firmly cement into a unitary body or knot, one end of the bristles which are to form the brush. The portion of the bristle bunch treated with the binding compound is indicated at 9 in Fig. 5. As a further step in the manufacture of the brush, the binding material is allowed to 5 suitably age to a desired state or extent, whereupon the ferrule is forced over the portion 9 and is placed in the finally desired position relative to the bristle-body, as shown in Fig. 6. This position is such that the wing portions of the 10 bristle butt extend into the ferrule a distance sufficient for the purposes of retaining the bristle-body, as a whole, firmly in the ferrule and retaining the individual bristles firmly in the knot, as will be more fully explained hereinafter. For these purposes the wing portions need not extend into the ferrule to a greater 15 distance than is customary with respect to bristle knots having square cut butt ends. In general it may be said that the wing portions need not extend more than about $\frac{1}{2}$ inch into the ferrule. In larger sized brushes they may need to extend 20 into the ferrule slightly more than half an inch while in smaller brushes they need not extend into the ferrule even as much as this. Viewed 25 from another angle it may be said that the winged end of the knot should extend into the ferrule far enough to locate the bottom of the valley 7 say between $\frac{1}{8}$ and $\frac{1}{4}$ of an inch or even less above a plane extending across the lower edges of the ferrule. A desired quantity of the same 30 or other suitable bonding material is then placed in the ferrule 2, Fig. 6, to form a portion 10 above the bristle knot, and the unit is subjected to processing which finally solidifies the bonding material and causes the parts 9 and 10 to unite and form a unitary base adhering to the ferrule and having the bristle ends firmly and fixedly embedded therein, thus forming a sub-assembly 35 to which any suitable type of handle may be attached by means of the ferrule. The processing of the binding material, when a rubber compound is used, is commonly known as vulcanizing, but it will be understood that other adhesive, 40 binding substances may be employed, if desired, and subjected to appropriate processing conditions.

As is well known, certain types and sizes of brushes are subjected to severe strains in use, and are further subjected to various conditions and treatments which tend to loosen the bristle-body from the ferrule and to expand this body with a consequent distortion of the encasing ferrule. To reinforce the brush and strengthen it so as to prevent such deformation, it is desirable to further anchor the bristle body 1 in and to the ferrule 2, and to so clamp the opposed sides of the latter as to resist the distorting forces. For this purpose holes may be made in the ferrule and the adjacent bristle body and headed nails or rivets 11 of suitable length may be driven in the holes and through the bristle unit. The exposed ends of these nails or rivets opposed to the heads may then be clinched, 45

peaned or otherwise set in a manner to make the bristle-body and its surrounding ferrule, a mechanically and firmly connected unit.

Reverting to the matter of strength and particularly the resistance to strains imparted in the normal use of the brush, it is desirable to anchor within the ferrule a fairly substantial portion of the cemented butt of the bristle body itself. This permits the strains incident to the use of the brush to be borne by a stronger body, i. e., a mixture of bristles and cement, than the cement or binding filler alone. It has been found unsatisfactory to depend on anchorage through the filler alone due to its structural weakness. Now in accordance with the present invention the winged structure, which is a combination of bristles and bonding agent, serves very effectively to bear the strains imparted in the use of the brush, particularly in view of the fact that the wings are reinforced or backed by the binding filler provided in the valley 7. The resistance to strains is equally as good as if the bristle butt were sheared straight across and extended into the ferrule the same amount as the wings of the improved construction. Yet there is a substantial saving in the bristles because the average amount to which they extend into the ferrule is considerably reduced. While, with this arrangement, the bristles which terminate adjacent the bottom of the trough 7 extend into the ferrule only a slight distance, it has been found that they are firmly held in the bristle-body by virtue of the action of the cementing agent and the clamping effect of the outer bristles forming the wings. On the other hand, if the innermost bristles do not extend into the ferrule a slight distance they will have a tendency to tear loose from the knot in the course of severe usage.

When nails or rivets are employed to reinforce the construction, as explained above, these may be passed through the cemented end of the bristle body just below the bottom of the valley 7, as shown in Figure 7, which will insure maximum 50 strength and avoid any danger of having the nails form an opening or split to the end of the bristle body. However, substantially equal strength can be attained by passing the nails merely through the wings 8 above the bottom of the trough or valley 7 so that a part of the nails will also be anchored in the downward extension of the binding compound 10, as shown in Figs. 3 and 4. This feature of the improved brush brings about a substantial saving in the length of the bristles. Inasmuch as the nails 55 11 will ordinarily be driven through the ferrule at a given distance, less than a quarter of an inch in the average brush, from the lower edge of the ferrule, preferably adjacent a lower bead or between a pair of beads extending around the ferrule near its lower edge, that portion of the bristle body that is held within the ferrule may be reduced to a minimum by adopting this feature of the present invention. Thus a brush of given size that has its bristles projecting a given length from the lower edge of the ferrule, is produced with minimum bristle length.

As a special modification the invention may be applied to brushes having a substantially flat operative end 13a, instead of the chisel end and particularly where such brushes have the outer faces or sides composed of bristles of a kind or grade different from those of the inner por-

tion of the bristle-body. As shown in Fig. 8 a layer of bristles, 12, 12 forming each side of the bristle-body is of a length greater than that of the mass 13 therebetween, the combination being so laid and butted as to produce a valleyed section 14 with the side winged portions 15, 15 at the upper end of the bristle body. If desired, the structure might be such as to provide a plurality of valleys with one or more dividing layers of bristles. One such dividing layer is illustrated in the brush of Fig. 9 in which 12, 12 are the outer layers, 15 a dividing layer and 13', 13' the valleys formed between these layers. As in the illustrated forms hereinbefore described this particular construction also permits the use of a minimum length of bristle in portions of the brush body as a result of the wing-like extensions of the outer layers and possible intermediate layer or layers. It will be understood that nails may be inserted as described and as shown at 11 in Fig. 9.

Fig. 10 illustrates the application of features of the invention to another type of brush in which an inserted plug 16 forms a part of the butt end of the bristle body. In other respects this form of the brush is shown as similar to that illustrated in Figure 3 but it will be understood that it might follow the construction of any of the modifications hereinbefore described. When such an inserted plug is used it brings about an inward tapering of the bristle body toward the lower end which may be supplemented by the chisel-like formation of the group of bristles themselves.

While certain illustrative forms of brushes embodying the principles and features of the present invention have been described in considerable detail it will be understood that numerous other variations and modifications may be made and that the features may be applied to various types of ferrules, with or without nails, rivets or other clamping devices, without departing from the scope of the invention. It will be understood that features disclosed in connection with one embodiment may be utilized, if desired, in connection with one or another of the other embodiments. In general, it may be said that the invention provides a brush having a given effective bristle length, i. e., from the bottom of the ferrule to the tips of the bristles, with a minimum actual bristle length and without materially weakening the construction of the brush as a whole.

What is claimed is:

1. A brush comprising a bristle body, a ferrule surrounding a portion of said bristle body, said bristle body being formed to provide a depression in its upper end defined by upwardly extending wing portions and to provide a complementary chisel-like formation at its lower end, cementing means permeating substantially the entire upper end of the bristle body within the ferrule for bonding together the bristles in and adjacent the wing portions, and additional cementing means bonded to form an integral unit with said first-mentioned cementing means and filling said depression, the said upper end of the bristle body extending into the ferrule a sufficient distance to retain firmly in the bristle body the innermost bristles adjacent the bottom of said depression but only to such extent as to place

the bottom of said depression not more than about three-sixteenths of an inch above the lower edge of the ferrule, the construction being such as to effect a saving in the length of the bristles employed while providing a strength substantially equal to that of a brush in which the bristle knot is square-cut at its upper end and is inserted in the ferrule to the same extent as said wing portions.

2. A brush comprising a bristle body, a ferrule surrounding a portion of said bristle body, said bristle body being formed to provide a depression in its upper end defined by upwardly extending wing portions and to provide a complementary chisel-like formation at its lower end, cementing means permeating substantially the entire upper end of the bristle body within the ferrule for bonding together the bristles in and adjacent the wing portions, and additional cementing means bonded to form an integral unit with said first-mentioned cementing means and filling said depression, said wing portions extending into the ferrule a distance no greater than the usual extent of a bristle knot having its upper end square-cut, the construction being such as to effect a saving in the length of the bristles employed while providing a strength substantially equal to that of a brush in which the bristle knot is square-cut at its upper end and is inserted in the ferrule to the same extent as said wing portions.

3. A brush comprising a bristle body, a ferrule surrounding a portion of said bristle body, said bristle body being formed to provide a depression in its upper end defined by upwardly extending wing portions and to provide a complementary chisel-like formation at its lower end, cementing means permeating substantially the entire upper end of the bristle body within the ferrule for bonding together the bristles in and adjacent the wing portions and filling said depression to form an integral unit with the bristle body, said upper end extending into the ferrule only a sufficient distance to retain firmly in the bristle body the innermost bristles adjacent the bottom of said depression, and fastening means extending through said ferrule, said wing portions, and the cementing means within said depression, the construction being such as to effect a saving in the length of the bristles employed while providing a strength substantially equal to that of a brush in which the bristle knot is square-cut at its upper end and is inserted in the ferrule to the same extent as said wing portions.

4. A method of making a brush involving a saving in bristle length without sacrificing any strength which comprises forming a group of bristles of substantially the same length into a body having a chisel-like formation at one end and a complementary depression at its other end, applying a cementing substance to said other end of said body and permeating the same with said substance adjacent said depression, permitting said substance to only partially age and solidify, placing said end with the partially solidified cementing substance in its finally desired position in a ferrule, adding more of the same cementing substance to fill said depression, and applying a handle to said ferrule.

LAWRENCE S. HEWES.
